PHONOGRAPH TONE ARM

Walter T. Heintze, New Canaan, Conn., assignor to
Rek-O-Kut Company, Long Island City, N. Y., a firm

Application May 3, 1956, Serial No. 41,333

Term of patent 14 years

(Cl. D26—14)

Fig. 1.

Fig. 2.

Fig. 3.

Fig. 4.

Fig. 5.

Fig. 1 is a perspective view of a phonograph tone arm embodying my new design;

Fig. 2 is a top plan view thereof;

Fig. 3 is a side elevational view showing one side thereof;

Fig. 4 is a side elevational view thereof showing the opposite side; and

Fig. 5 is a rear end elevational view thereof.

I claim:

The ornamental design for a phonograph tone arm, as shown.
